(57) **CLAIM**

We claim the ornamental design for a debris pan, as shown and described.

DESCRIPTION

FIG. 1 is a first side view showing our new design for a debris pan;

FIG. 2 is a front view showing the design of FIG. 1;

FIG. 3 is a second side view showing the design of FIG. 1;

FIG. 4 is an upper perspective view showing the design of FIG. 1;

FIG. 5 is a perspective side view showing the design of FIG. 1;

FIG. 6 is a perspective side view showing the design of FIG. 1;

FIG. 7 is a bottom view showing the design of FIG. 1;

FIG. 8 is a top view showing the design of FIG. 1;

FIG. 9 is a top cross-sectional view showing the design of FIG. 1;

FIG. 10 is a perspective cross-sectional side view showing the design of FIG. 1;

FIG. 11 is a side cross-sectional view showing the design of FIG. 1; and,

FIG. 12 is a side cross-sectional view showing the design of FIG. 1.

In FIGS. 1-12, the broken lines are for purposes of illustration only, and do not form a part of the claimed design.

1 Claim, 7 Drawing Sheets
